UPHOLSTERY EDGINGS

Albert M. Bank, Jersey City, N. J.

Application March 14, 1957, Serial No. 645,933

11 Claims. (Cl. 155—184)

The present invention relates to upholstery edgings or welts which are mounted along the front edge of seat structures and in present-day upholstery construction, they are usually secured along the border wire of spring assemblies. Besides their protective function, these welts support the forward ends of the seat cushions, make a proper bend or "break" in the underside of the cushion to hold it properly positioned on the seat against forward shift and to maintain the cushion downwardly rearwardly sloped at seat edge. These welts are of resilient quality, more or less, and after some time of being subjected even in normal use to the distorting forces offered by persons sitting, that they get deformed and disrupt the orderly look of the furniture because of the haphazard positions assumed by the cushions at front edge when the seat is not in use and of course, such distortion, hampers their intended function.

It is therefore the principal object of this invention to provide a novel and improved welt construction which will avoid the occurrence of the mentioned objectionable conditions. To attain this important object, I provide a welt in which the cushion-supporting region thereof is never subjected directly to force of the weight of persons seated, and upon the seat being cleared, such region, though having shifted, will automatically assume its initial position to properly raise and support the front edge of the seat cushion.

A further object of this invention is to provide a welt of the character described and having the attributes set forth, which is of novel and improved construction, reasonably cheap to manufacture, easy to mount and efficient in carrying out the various functions for which it is designed.

Other objects and advantages will become apparent as this disclosure proceeds.

In the practice of this invention, one form this welt may assume, comprises a first core section provided with attachment fins, one rearwardly horizontal and the other extending downwardly from said first core section, forwardly of the first attachment fin. The first core section carries a second core section along the top thereof. Said second core section and the attachment fins are all coextensive lengthwise with the first core section. The juncture of the core sections is of course lengthwise of the welt structure and has resilient quality and serves axis-like for the swing movement of the second core section. Such juncture is comparatively thin. The transverse cross-section of the second core section may be substantially round. The cross section of the first core section may also be round. Other shaped cross sections may be chosen, but it is essential that the juncture of the core sections shall be comparatively thin and have some resilient quality.

It is preferred that the line of juncture of the two core sections shall be along the forward surface of the first core section and it is mandatory that upon application of a downward force on the second core section, that said second section shall be swung downwardly forwardly

of the first core section. It is best that the core sections shall be at least near tangency longitudinally. It is also preferred that the plane passing through the center lines of both core sections shall make an angle of between 5 45 to 60 degrees with the horizontal plane tangent to the underside of the first core section. I may also note, that if desired, the entire welt may be an extrusion of rubberized or rubber-like material, or as heretofore, there may be a fabric or paper covering for the cores out of which 10 covering, the attachment fins are formed.

A more detailed description will now be given.

In the accompanying drawings forming part of this specification, similar characters of reference indicate correspondent parts in all the views.

15 Fig. 1 is a fragmentary perspective view showing a welt embodying the teachings of this invention.

Fig. 2 is a diagrammatic end view of the welt shown in Fig. 1, indicating the condition and position of the 20 components thereof when subjected to the weight of a person seated and its normal condition when the seat is clear.

Fig. 3 is a fragmentary top plane view of a spring assembly along whose border wire, the welt is shown mounted.

25 Fig. 4 is similar to Fig. 1, but shows the welt as an extrusion; all components being integral.

Fig. 5 is a section of modified core structure.

In the drawings are shown forms of edgings this invention may assume. The numeral 15 designates one of 30 them generally. It consists of a first welt body 16 provided with the lengthwise attaching fins 17 and 18, which are preferably tangent thereto, one downwardly in front and the other rearwardly from its undersurface.

35 Atop the first welt body 16 and lengthwise thereof, is a second welt body 19 preferably of smaller thickness and overhanging it forwardly. The cross sections of the welt bodies may be circular but of importance is that they form a channel 20 along the front of the edging 15 to permit forwardly downwardly pivotal movement of the upper welt body 19. Their construction may comprise cores 16', 19' of crumpled or twisted paper or of other materials well known in this art. Such cores are encompassed by a fitted covering 21 which may be of burlap or other suitable sheeting.

40 As is well known, the attaching fins 17, 18 may be formed of the covering as shown in Fig. 1 for example. The front and rear parts of the covering are preferably joined between the cores as by the lines of stitching indicated at 22. It is also practical to make this edging in one piece as an extrusion of rubber-like material as shown in the embodiment illustrated in Fig. 4. Here as in Fig. 1, the junction 23

45 is comparatively of thin section. Regardless of material used, the edging of course, shall have resilient quality; 50 especially said junction 23.

55 The edging 15, or 15' may be mounted along the border wire of a spring assembly in upholstery. It is laid on so that the fin 17 is in front of and abuts the border wire 28 while the rearward fin 18 is on top of the springs 60 24. The fins may be attached by hog rings 25, 26 to said border wire and the top turns of the springs 24 respectively or in other suitable manner.

When the edging is subjected to the weight of a person seated on a chair or sofa whose seat's front edge 65 is provided with this edging the welt body 19 will be swung downwardly to position 19a as shown in Fig. 2, thereby flexing the juncture of the welt bodies 16, 19 and will cause some distortion in the cross-sectional form of said welt bodies as indicated in dotted line in said Fig. 2. It is to be noted that a considerable part of the stress is spent at such junction and there occurs less of deformation of the corpus of the edging to assume its shape in use when the seat is occupied. It is evident that

when the seat is clear, the edging 15 or 15' will automatically assume its original condition to raise the front region of the seat pillows of the upholstered article.

The cores 16', 19', may be of felt material or other suitable substances known in the art, though twisted paper is popular in present day manufacture. Also, said core may be a hollow resilient tube of plastic or rubber-like material 30 or such tube may be filled with twisted paper 31, or felt and the like.

This invention is capable of numerous forms, for instance the edging sections may be other than of round cross section as shown, and applicable for other uses without departing from the essential features herein disclosed. It is therefore intended and desired that the embodiments shown shall be deemed illustrative and not restrictive and that the patent shall cover all patentable novelty herein set forth; reference being had to the following claims rather than to the specific description herein to indicate the scope of this invention.

I claim:

1. In an edging for the front top edge of a seat of an article of furniture having a seat to be upholstered, a first horizontal welt body, means thereon for securing same along such edge and a second welt body atop and along the first welt body and secured thereto therealong for forwardly downwardly resilient pivotal movement in relation thereto; said welt bodies forming a channel lengthwise of the edging on the front surface thereof; said channel being unobstructed and remaining so when the edging is in use; the second welt body overhanging the first welt body in a forwardly direction; said edging having resilient quality.

2. The edging for upholstery as defined in claim 1, wherein the mentioned means comprises two lengthwise fins; one extending rearwardly and the other downwardly from the first welt body.

- 4
3. The edging for upholstery as defined in claim 2, wherein the rearward fin extends from the bottom and the second fin extends from the front of the first welt body.
5. The edging as defined in claim 2, wherein all its parts are integral.
10. The edging as defined in claim 1, including a covering fitted on and encompassing the two welt bodies and where the mentioned means comprises two lengthwise fins; one extending rearwardly and the other downwardly from the first welt body; said fins being formed of said covering.
15. The edging as defined in claim 5, wherein the rearward fin extends from the bottom and the second fin extends from the front of the first welt body.
7. The edging as defined in claim 6, wherein the front and rear parts of the covering are joined between the welt bodies.
20. The edging as defined in claim 1, wherein the junction of the welt bodies is comparatively thin and the welt bodies are comparatively thick.
9. The edging as defined in claim 8, wherein the first welt body is thicker than the second welt body.
25. The edging as defined in claim 1, wherein the forward portions of the welt bodies are respectively substantially of semi-circular cross-section.
11. The edging as defined in claim 1, wherein the mentioned means comprises two lengthwise fins; one extending rearwardly and the other downwardly from the first welt body and both are substantially tangent thereto.
